UNITED STATES PATENT OFFICE.

SAMUEL D. MOTT, OF PASSAIC, NEW JERSEY, ASSIGNOR, BY MESNE ASSIGNMENTS, TO STANDARD POWER COMPANY, OF NEW YORK, N. Y., A CORPORATION OF NEW YORK.

HYDROCARBON-BURNER.

SPECIFICATION forming part of Letters Patent No. 695,223, dated March 11, 1902.

Original application filed December 4, 1900, Serial No. 38,704. Divided and this application filed June 1, 1901. Serial No. 62,809. (No model.)

To all whom it may concern:

Be it known that I, SAMUEL D. MOTT, of Passaic, Passaic county, New Jersey, have invented certain new and useful Improvements in Hydrocarbon-Burners, of which the following is a full, clear, and exact description.

My invention relates to improvements in hydrocarbon-burners; and the object of my invention is to produce a very cheap and simple burner of this class which is preferably relatively flat and thick, which has a series of air-jets extending through it from bottom to top, an interior gas-chamber and gas-vents in close proximity to the gas-jets, which is adapted to be used in connection with any suitable hydrocarbon-injector or any device adapted to feed a volatilized hydrocarbon to it, and which is constructed so as to be readily heated to incandescence and to retain its heat sufficiently to again ignite the hydrocarbon even though the supply may have been temporarily shut off.

To these ends my invention consists of certain features of construction and combinations of parts, which will be hereinafter described and claimed.

Reference is to be had to the accompanying drawings, forming part of this specification, in which similar figures of reference refer to similar parts throughout the several views.

Figure 1 is a plan view of my improved burner. Fig. 2 is a vertical cross-section on the line X X of Fig. 1, and Fig. 3 is a cross-section of a slightly-modified form of the burner.

The burner 45 is preferably flat and of a generally circular shape, although the shape is not material, and it is made in two pieces—40 to wit, the dishing top plate 46 and the base-plate 47, the latter being preferably ribbed on the bottom to give it necessary strength. The top plate is flanged, as shown in Fig. 2, and the two parts screwed or otherwise fastened together. The base-plate 47 has cast integral with it a series of air-jets 48, which extend upward through the gas-vents 48^a in the top plate 46, and the top plate has also other vents 48^b to make sure that there is

sufficient room for the expanded fuel to find 50 its exit.

It will be noticed that the inverted-dish shape of the top plate 46 forms a gas-chamber in the burner in which the hydrocarbon may accumulate, and as there is a good deal of 55 metal to the burner and it is heated to incandescence it gives the hydrocarbon an opportunity to gasify and so be rendered more perfectly combustible.

The burner 45 has connections 49, into which 60 suitable injectors 10 may be made to deliver, and these injectors should be of such a nature as to discharge a highly-volatilized hydrocarbon into the chamber of the burner. A suitable device of this kind is the burner de- 65 scribed in my application for Letters Patent, Serial No. 38,704, filed December 4, 1900, of which application this case originally formed a part.

In addition to the connections 49 the burner 70 is provided with a depressed connection 50, which may also be provided with a burner or injector 10, and this may be a pilot-burner or injector which can be kept going when the other connections are shut off, so that sufficient 75 fuel will be supplied to keep the burner hot without creating any intense heat, thereby adapting it especially to automobile-work and keeping it in readiness to quickly throw out a great heat when the full fuel-supply is 80 turned on. The pilot-chamber 50 is in open communication with the main chamber of the burner, as shown in Fig. 2; but when only the pilot-burner is used there will be merely sufficient heat to keep the casting hot, and 85 when the main supply is turned on it will at once gasify and burn.

In Fig. 3 I have shown a modification of the burner illustrated in Figs. 1 and 2, and in this case I use a drum 51, which has, preferably, 90 separate bottom and top plates 51^a and 51^b. It has a connection 49 for a burner or injector 10 and is provided with a central chamber 52 to connect with a pilot-burner or injector, and for this is a central vent 53 for the flame 95 of the pilot-burner. The drum has also a lower chamber 54, connecting with the chamber 52 and serving as a reservoir for the hy-

drocarbon which enters the drum, and a chamber 55, near the top of the drum, which receives the atomized fuel from the burner or injector 10 first mentioned. From this burner the 5 hydrocarbon issues through the vents 51^a, which are in close proximity to the vertical air jets or holes 56, which extend upward through the burner.

Having thus described my invention, what 10 I claim as new, and desire to secure by Letters Patent, is—

1. A hydrocarbon-burner comprising a compact flat and horizontally-separable drum having a central depressed chamber and air-jets extending vertically through it from top to bottom, gas-openings through the drum-top these being arranged around the air-jets, a fuel-supply discharging into the pilot or depressed chamber, and fuel-supplies for the 20 main chamber all substantially as described.

2. A hydrocarbon-burner comprising a relatively flat two-part drum in the form of a casting, the lower part having cast integral therewith on a depressed chamber for a pilot or secondary fuel-supply and having a series of jet-pipes for air leading upward from it and the upper part being adapted to fit upon the lower part so as to form a main gas-chamber between the two parts, the upper part having also openings to surround the air-jets, and connections by which a fuel-supply may be delivered to the main gas-chamber and to the secondary chamber. 25

In testimony whereof I have signed my name to this specification in the presence of 30 two subscribing witnesses.

SAMUEL D. MOTT.
